ELECTRICAL CONTACT

Townsend M. Gunn, Attleboro, and Walter J. Wilhelm, Plainville, Mass., assignors to Metals & Controls Corporation, Attleboro, Mass., a corporation of Massachusetts

Application September 10, 1943, Serial No. 501,804

8 Claims. (Cl. 200—166)

1

This invention relates to electrical contacts, and with regard to certain more specific features, to means for attaching said contacts to thin sheets of materials such as composite thermostatic materials.

Among the several objects of the invention may be noted the provision of means for attaching contacts to thin sheets such as composite thermostatic materials and the like, without destructive action on said sheets; the provision of means of the class described which has the beneficial characteristics of both welded and soldered attachments without many of the disadvantages of either; and the provision of an attachment of the class described which is very accurate permanent and reliable. Other objects will be in part obvious and in part pointed out hereinafter.

The invention accordingly comprises the elements and combinations of elements, steps and sequence of steps, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a top plan view of a contact embodying the invention;

Fig. 2 is a bottom plan view of Fig. 1;

Fig. 3 is a cross-section of a composite strip prior to a forming operation;

Fig. 4 is a cross-section illustrating a forming operation;

Fig. 5 is a vertical section taken on line 5—5 of Fig. 1;

Fig. 6 is a cross-section at location 6—6 of Fig. 2 but showing the finished contact attached to a bimetal sheet;

Fig. 7 is a side elevation of the finished contact;

Fig. 8 is a side elevation showing how the assembly of Figs. 6 and 7 is made on a spot welder;

Fig. 9 is a section showing an alternative form of contact button before attachment; and

Fig. 10 shows the button of Fig. 9 in attached position.

Similar reference characters indicate corresponding parts throughout the several views of the drawing.

It is commonly necessary to attach electrical contacts to thin sheets such as of bimetallic thermostatic material which, due to its thinness of section, is easily damaged by the attaching process. Electrical spot-welding has been found to

2

be one of the best methods of making such an attachment, but even with it certain difficulties are encountered in practice. This is because the bimetal is usually a high-resistance material, such as for example a nickel-steel and invar combination, the total thickness of which is, for example, of the order of .006 to .016 inch. An example of the contact to be attached is a button composed of a silver facing on a steel or Monel backing, the total thickness of which button is, for example, of the order of $\frac{1}{16}$ to $\frac{1}{8}$ of an inch. Other metals and thicknesses are sometimes used, but the above are exemplary.

No attempt is ordinarily made to weld silver directly to bimetal, because silver has such a low resistance that it would require an excessive amount of current to bring about its fusion to the bimetal; and then the high-resistance bimetal would be so overheated by this amount of current that it would burn away. This overheating is due not only to the high-resistance characteristics of the bimetal but also to its thin cross section. Therefore, heretofore it has been the practice to employ the steel or Monel backing mentioned in order to more closely match the relative resistance of the actual surfaces to be joined, and thus be able to use a lower value of current. Nevertheless, some difficulties are met with in the case of very thin bimetal having rather high resistance qualities. The present invention overcomes these difficulties.

Referring now more particularly to the drawing, numeral 1 indicates a contact button generally, and numeral 3 the thin bimetal strip to which the contact 1 is to be attached. The contact button 1 is composed of a steel or Monel backing 5 having welded thereto in the usual manner a silver face 7. The buttons are made from a sheet constituted by welded steel (or Monel) and silver components (see Fig. 3).

The present invention comprises applying a layer 13 of solder about .002 inch thick on the steel or Monel sheet opposite the silver sheet, preferably prior to punching, as indicated in Fig. 4. Then the organized silver-steel-solder sheet is placed in a coining press to form the individual buttons as shown in Fig. 4. A matrix die 6 provides the convex surface for the silver sheet 7. This convex surface is shown at the bottom in Fig. 4. The opposite matrix die 8 has a face which impresses upon the solder-covered steel or Monel face a grid-like impression shown at the top of Fig. 4. The face of this contour is shown in Fig. 2. The grid-like contour is squeezed into the steel or Monel backing through the solder

without removing the solder, and the result is a grid-like back facing in the steel or Monel which is entirely covered with solder of about the same grid-like contour.

After the above forming operation has been completed, the contacts then appear as in Figs. 1, 2 and 5. They then comprise a silver facing on a steel or Monel backing, the latter having a solder-covered grid-like rear face. This grid-like back face is the one which is to form the attachment to the thermostatic strip 3. In the example shown, the raised portions (Figs. 2 and 5) constitute about 58% of the area, and the depressed channel parts constitute about 42% of the area. These proportions are subject to variation.

Attachment of the button 1 to the strip 3 is made in a spot-welding machine 18 (Fig. 8) having high-conductivity, cold-operating electrodes 17. A hot-electrode welder is not used, such as for example one employing carbon electrodes. This is an important point, since it is desired to cause the heating for welding and soldering to occur only near the faces of the raised grid portions 9 which faces are on the interior of the joint, and not by heat conduction from an electrode through the silver 7, steel 5 and strip 3. The reason for this is that in the latter case the temperature gradient would be from the electrodes toward the grids 9, thus subjecting the entire thickness of the strip 3 to a higher temperature than necessary for a given temperature at the point of welding and soldering. With the high conductivity cold electrodes in the welding machine, the parts 9 are first heated to a higher temperature than the surrounding parts simply because they have a smaller cross section than the adjacent parts and thus heat up faster and accomplish the interior welding and soldering before overheating or burning of the strip 3 can occur.

We have found that the use of carbon electrodes caused extensive annealing of the bimetal, due to the length of time required in the total attaching cycle. With the carbon electrodes using solder alone, it is necessary to hold the electrodes clamped together to position the contact on the bimetal until the solder solidifies. Also, the heating part of the cycle is slow because of the fact that if sufficient current is used to heat the button and bimetal rapidly, the silver surface of the button will melt first because the heat engendered therein comes, for a large part, from the carbon electrodes.

In the present method, the grid projections act as rapid heaters for the solder at the one particular place where it is necessary to have this heat. This heat may reach 2700° F. due to the welding that takes place. However, it occurs so rapidly that little or no annealing of the bimetal around the contact takes place, yet, due to the high temperature, the solder immediately flows during the cycle. Also, the weld that is made serves to clamp the contact on the bimetal in position while the solder solidifies.

It is to be understood, as to Fig. 8, that the usual pressure of the welding machine electrodes is applied and current traverses the button 1 and strip 3, the solder on the faces of the raised grid portions 9 is melted and is squeezed out laterally into the grooves 11 therebetween. In this position the solder takes up its holding functions. As the solder disappears from under the parts 9, they come into contact with the strip 3 and are joined thereto by direct spot-welds.

The grooves 11 accommodate enough solder so

that not enough flows out around the edge of the button to make the usual undesirable uneven collar of solder which is often seen on ordinary soldered contacts. Any excessive uneven lateral collar has various electrical disadvantages which it is important to avoid if possible. For example, it often prevents the most desirable current distribution around a contact. A typical finished result of the invention is shown in Figs. 6 and 7.

The attachment is by means of welding only at the then practically solderless raised faces 9 and by the solder 13 now filled in the grooves 11. The result is a relatively heavy contact attached both by welding and soldering (but in different areas) to a relatively thin bimetal sheet. This makes an exceedingly strong joint in which no damage has been done to the thin sheet 3. In addition the attachment is relatively accurate and clean-cut around the edges of the button 1. The welded part of the contact is constituted by a field of separated areas, and the soldered parts are constituted by a network of solder lines. The relative areas of the field of squares and of the network can be varied somewhat, and also the shape of the grids can be varied. The values above given are for a $\frac{1}{4}$ inch button about .06 inch thick having a silver facing on a steel or Monel backing attached to a bimetal strip of chrome-steel alloy and Invar totaling about .009 inch thick, the attachment being made on the chrome-steel side of the strip.

Reduction of attachment areas of buttons has heretofore been attempted by providing a single small area in order to gain the resistance needed for temperature increase at the welding point. In practice this involved a current density of about 33,000 amperes per square inch or higher in the case of a $\frac{1}{4}$ inch contact necked down to $\frac{1}{16}$ inch to provide a single area of weld of about .003 inch area. If the whole $\frac{1}{4}$ inch area were to be welded down the current density would be the same, but the total current required would be enormously greater.

It has been suggested heretofore to use multiple projections on a contact instead of a single projection to increase resistance and localize heat without overheating, but the current-carrying capacity of such a joint will nowhere equal the capacity of the present joint, nor will it have as great a mechanical strength.

It will be understood that suitable flux may be used between the button 1 and strip 3 during the soldering and welding process, but this is not always necessary where the component of the strip 3 which is adjacent to the button 1 does not oxidize quickly.

By this invention several things are accomplished. The weld serves to give mechanical strength to the joint and also high conductivity, due to the autogenous joint where it occurs. It also acts as a clamp while the solder solidifies. The solder gives the additional electrical contact between the contact button and the thin bimetal which the welded zones do not supply. Furthermore, the projections serve as heaters for the solder to enable an extremely short soldering-welding time to be used to avoid unwanted annealing. Therefore, there results an attachment which covers the entire area of the contact button, is mechanically strong, and is done with lower power and less deleterious annealing than would be the case if a joint of the same area were made by other known methods.

As an example above, we have used a thin sheet of high-resistance bimetal. However, the effect

can be advantageously used where a heavy contact is to be soldered to a thin sheet of copper. In that case the grid form can be used if the contact has a relatively thick portion of steel, as shown above. However, if it is possible to use a thin section of the high-resistance heater metal, next to the solder, the grid form may not have to be used, as indicated in Fig. 9 wherein numeral 21 is a silver contact, 23 is a flat disc of high-resistance heater metal and 25 the solder. In 10 this case when attachment is made, the heater metal 23 melts the solder 25 and forms a soldered connection to the sheet 27 as shown in Fig. 10.

In this case only a soldered connection is desired to the thin low-conductivity copper sheet 27. Thus, the layer 23 of high-resistance metal acts as an efficient adjacent heater for the solder while preventing destruction of the thin sheet to which the contact is being attached, just as it prevents destruction in the bimetal sheet in the case of a contact which is welded, as above described.

It is to be understood that in both forms of the invention any inaccuracies of engagement between the contact areas will automatically be filled in with solder which will perform the desired holding functions.

In view of the above, it will be seen that the several objects of the invention are achieved and other advantageous results attained.

As many changes could be made in the above constructions and processes without departing from the scope of the invention, it is intended that all matter contained in the above description or shown in the accompanying drawing shall be interpreted as illustrative and not in a limiting sense.

We claim:

1. An electrical contact comprising a member having a relatively low-resistance face and a 40 relatively high-resistance back to which said face is attached, said back being provided with a field of spaced, raised welding areas with depressed spaces therebetween, solder in said spaces, and a support attached to said back directly at said raised areas and through the solder in said spaces.
2. An electrical contact assembly comprising a relatively thin bimetallic support, a contact button comprising a relatively high-resistance element adjacent said support and a relatively low-resistance element on its other side, said button being directly attached to the support over a certain area, and solder connecting the button to the support over another area.
3. An electrical contact assembly comprising a relatively thin bimetallic support, a contact button comprising a relatively high-resistance element adjacent said support and a relatively low-resistance element on its other side, said button

being directly attached to the support over a certain area, and solder connecting the button to the support over another area, said directly attached and soldered areas being both substantially within the periphery of the button.

5 4. An electrical contact comprising a button having a low-resistance face and a high-resistance back attached to said face, said back having its rearward face formed as a grid of raised and low portions, a support contacted by said raised portions and directly attached thereto, and solder in said low portions attaching said button and support.

15 5. A contact comprising a relatively low-resistance conducting face member, a relatively high-resistance heater member forming a backing for said face, solder on said backing member for attachment to a support, said backing member having a high enough relative resistance with respect to the resistance of the face member so that upon application of current to the contact 20 said solder is transformed into a fastener between the backing and the support without substantially damaging either the face member, the support or the backing member.

25 6. A contact comprising a relatively low-resistance conducting face member, a relatively high-resistance heater member forming a backing for said face, solder on said backing member for attachment to a support, said backing member having a high enough relative resistance with respect to the resistance of the face member so that upon application of current to the contact 30 said solder is transformed into a fastener between the backing and the support without substantially damaging either the face member, the support or the backing member, said current being sufficient also to weld the backing member to the support without substantial damage.

35 7. A contact for attachment to supports comprising a face made of material of relatively high conductivity, a solder fastening part, and a layer of relatively high-resistance metal between the face and the solder adapted upon application of sufficient current to melt the solder without substantial damage to the supports or the face.

45 8. A contact for welding and soldered attachment to supports comprising a face made of material of relatively high conductivity, a solder fastening part, and a layer of relatively high-resistance metal between the face and the solder, and having a reticulated face for positioning against the support and adapted upon application of sufficient current to melt the solder and to weld the reticulated face of the high-resistance metal to the bimetallic sheet without substantial damage to the latter or the face.
